UNITED STATES PATENT OFFICE.

EMMIT G. LATTA, OF FRIENDSHIP, NEW YORK, ASSIGNOR OF ONE-HALF TO
HARVEY A. MOYER, OF SYRACUSE, NEW YORK.

TYPE-WRITING MACHINE.

No. 843,831.

Specification of Letters Patent.

Patented Feb. 12, 1907.

Application filed February 2, 1905. Serial No. 243,834.

To all whom it may concern:

Be it known that I, EMMIT G. LATTA, a citizen of the United States, residing at Friendship, in the county of Allegany and State of New York, have invented a new and useful Improvement in Type-Writing Machines, of which the following is a specification.

This invention relates to ribbon mechanisms for type-writing machines, and more particularly to mechanisms for feeding the ribbon lengthwise and vibrating or moving it into and out of operative position in front of the printing-point in visible-writing machines in which the type-bars are arranged to produce the impressions at a point on the platen where they can be seen by the operator when the ribbon is moved away from its operative position over or in front of the printing-point.

The principal objects of the invention are to so connect the key-action and ribbon mechanism that the least power is utilized in the operation of the ribbon, thereby insuring a light touch and rapid easy operation of the machine; to provide simple, efficient, and desirable means whereby the ribbon can be vibrated to expose the writing after each impression or only upon the actuation of a key independent of the type-operating keys; to adapt the machine for the use of a narrow light ribbon, which is vibrated with each impression, or for a wider and heavier ribbon, which is vibrated only by the actuation of a special key or space-key; to provide a ribbon-vibrator free from working joints, thus reducing the power necessary for operating it; to relieve the type-bar keys of the work of feeding the ribbon lengthwise; to provide a simple and desirable printing-point index, which can be operated as desired to indicate the printing-point either after each impression or upon the actuation of the special operating-key for the ribbon-vibrator, and to improve the ribbon-operating mechanisms of type-writing machines in the various particulars hereinafter specified, and set forth in the claims. These objects are accomplished in part by providing the machine with two bars or parts arranged beneath and adjacent to the platen—one a universal bar operated by the several finger-keys and the other operated by the space-key or a special key, and

each constructed to support and operate a ribbon-vibrator; by operating the ribbon-feed mechanism by a motor or power device in which power is stored by the actuation of the space-key and which relieves the finger-keys except of the slight work necessary to control the operation of the motor or power device, and by providing an oscillating printing-point index adapted to be operated, as described, by either of the operating bars or parts for the ribbon-vibrator.

In the accompanying drawings, consisting of three sheets, Figure 1 is a broken plan view, partly in section, of parts of a type-writing machine, the carriage being omitted, but the position of the platen being indicated by broken lines and the universal bar being shown in its rearward or abnormal position. Fig. 2 is a longitudinal sectional elevation thereof, showing the carriage and other parts omitted from Fig. 1 and showing the universal bar and space-bar in their normal positions. Fig. 3 is a fragmentary sectional elevation of a guide and vibrator and associated parts for a wide ribbon. Fig. 4 is a detail section of the shank of the ribbon guide and vibrator and its holder. Fig. 5 is a fragmentary sectional elevation of the platen and a modified form of the ribbon guide and vibrator. Figs. 6 and 7 are respectively a detached side and front elevation, respectively, of the guide and vibrator for the wide ribbon. Fig. 8 is a fragmentary transverse sectional elevation of the machine substantially in the plane of the ribbon-spool shafts, showing the ribbon-feed mechanism. Fig. 9 is a sectional elevation, on an enlarged scale, in line 9 9, Fig. 12, of the ribbon-feed mechanism, and also showing a portion of the universal bar in its normal position. Fig. 10 is a similar view showing the position of the parts when the universal bar is moved rearwardly. Fig. 11 is a fragmentary sectional elevation, on an enlarged scale, in line 11 11, Fig. 8, of the ribbon-drive mechanism. Fig. 12 is a transverse section, on an enlarged scale, of the ribbon-drive mechanism in line 12 12, Fig. 11.

Like letters of reference refer to like parts in the several figures.

A represents the frame of the machine, which may be of any suitable shape and construction; B, the platen, which, as usual, is

journaled on a carriage *b*, which is movable transversely of the machine on a suitable guide and supporting track or bearings *b'* and the intermittent or step-by-step movement of which is controlled by an escapement mechanism, (not shown;) *C*, one of the type-bars, which are pivoted on a segment *c* below the platen and swing upwardly and rearwardly to make the impressions at the front side of the platen, and *E* the finger-keys, which are arranged in a keyboard located in front of the carriage and are operatively connected to the type-bars.

The machine illustrated is of that kind in which each type-bar is provided with two type and the carriage is mounted on a shift-frame *D*, which normally holds the platen up in position for printing with the upper-case type at the outer ends of the type-bars and is shifted downwardly (by means not shown) for printing with the inner or lower-case type. The type-bar action (illustrated in Fig. 2) is fully shown and described in my application for United States Letters Patent, filed January 17, 1905, Serial No. 241,456, and it is sufficient here to say that the finger-keys are arranged in banks or rows running transversely of the keyboard, and each key is mounted to reciprocate vertically on a key-lever *F* and link *f*.

G represents the universal bar or part operated by the finger-keys for tripping the carriage-escapement to effect the letter-spacing. The bar is arranged at the central portion of the machine, preferably extending from a point beneath the front portion of the keyboard upwardly and rearwardly passing over the type-bar segment between the two central type-bars and beneath the platen. The bar shown consists of two narrow strips of sheet metal arranged side by side, with their front ends spread apart and pivoted to arms *g* on a rock-shaft *g'*, journaled in suitable brackets *g''* on the front of the frame, while the rear end of the bar is pivoted to an arm or lever *g''*, which is pivoted on a bracket *g''* on the back of the frame and trips the carriage-escapement by a rearward thrust of the bar. The universal bar supports a ribbon-vibrator, and the object of spreading its front end is to better hold the bar and its vibrator in proper upright position. In that portion of the bar passing over the segment the strips are secured face to face to make the bar narrow, so as not to interfere with the type-bars, while in that portion of the bar underlying the keyboard the strips are spaced apart and connected by transverse rivets or pins *g''* for the engagement of arms on rock-shafts *H* for actuating the universal bar. The latter is held in its normal forward position and retracted after operation by a coil-spring *g''*, connected to a rod joining the swinging supporting-arms for the front end of the bar and to the front of the frame. In-

stead of the universal bar passing above the segment between the type-bars it could be offset to pass under the segment.

The actuating rock-shafts *H* for the universal bar (see Fig. 2) are arranged transversely under the keyboard, one beneath the fulcrum of the key-levers for each transverse row or bank of finger-keys, and are journaled on their ends in suitable bearings *h* at the sides of the frame. Each rock-shaft 75 has a depending central arm *h'*, which engages one of the pins *g''* of the universal bar, and a series of arms *h''*, which are parallel with the front arms of the key-levers *F* and bear against the lower ends of the stems of the 80 several finger-keys in one row or bank, so that when any key in the row or bank is depressed the shaft *H* beneath it will be rocked and thrust the universal bar rearwardly to the position shown in Figs. 1 and 10 to trip 85 the carriage-escapement. The rock-shafts *H* are returned to and held in the normal position by suitable springs *h''*, Fig. 1. A separate universal-bar-actuating shaft *H* for each row of keys is preferred, because the bar 90 with one actuating-shaft is lighter and easier to operate than would be a bar and actuating device or mechanism common to all of the keys; but for the purpose of this invention the universal bar could be reciprocated 95 by other actuating means or parts.

I represents the space-key, or key for tripping the carriage-escapement to effect the spacing independently of the type-bar action. The space-key preferably has two vertical stems pivoted to arms *i* on a rock-shaft *i'*, journaled in the brackets *g''* on the front of the frame, and is held in and returned after actuation to its normal raised position by a suitable spring *i''*, connected to one of the 105 arms *i* and to the frame.

K represents a bar or part, hereinafter termed the "space-bar," which is located at the central portion of the machine, preferably over and extending in the same general direction as the universal bar *G*. The space-bar, like the universal bar, is preferably made of two strips of sheet metal or a folded strip of metal, the two strips or portions being arranged close together, except at their rear ends, which spread apart. The front end of the space-bar *K* is offset upwardly to pass over the rock-shafts *H* and is pivoted to an upwardly-extending arm *k* on the rock-shaft *i'* for the space-key, and its forked rear 115 end is pivoted to arms on a rock-shaft *k'*, which is journaled in the bracket *g''* on the back of the frame and has an arm *k''*, which acts to trip the carriage-escapement each time the space-key is depressed. The forked 120 rear end of the space-bar, like the forked front end of the universal bar, holds the space-bar in upright position. The two bars *K* and *G* constitute supports for ribbon guides and vibrators, and the former reciprocates end- 125 130

wise like the latter; but the space-bar is arranged to act on the escapement by a forward movement, while the universal bar trips the escapement in its rearward movement, the purpose of the reverse action of the two bars being to provide two separate and distinct ribbon movements, as will be described. The two bars could be otherwise constructed and mounted to operate in a similar manner.

The ribbon L is connected at opposite ends to ribbon-spools l, placed on supporting-shafts, which are operated to feed the ribbon, as hereinafter explained, and the ribbon is supported between the spools and adjacent to the printing-point by a guide and vibrator, which may be supported and actuated by either the universal bar or the space-bar. The guide and vibrator M (shown in Figs. 1, 2, and 8) is secured to the universal bar and consists of a single piece of sheet metal having a forked upper end provided with upright guide slots or openings m, through which the ribbon passes, and a depending shank m', which enters and is detachably retained in a flanged upright holder m², fixed to or formed on the universal bar. The shank of the guide and vibrator is preferably bowed, as indicated at m³, Fig. 4, and of spring temper and is held in adjusted positions in the holder by the friction between these parts. When the universal bar is in its normal position, (shown in Fig. 2,) the guide and vibrator holds the ribbon in front of and below the printing-point, exposing the line being printed to view. When the universal bar is moved rearwardly by the operation of a finger-key, it carries the vibrator and ribbon with it, holding the ribbon directly in front of or over the printing-point at the instant the type-bar makes the impression. This vibrator is exceedingly light in weight and with a narrow ribbon, such as shown in Figs. 1, 2, and 8, adds very little work to the type-bar action and insures a light touch and easy operation of the finger-keys. The absence of working joints in the ribbon-vibrator contributes considerably to the easy movement of the ribbon and entirely prevents wear in this part. With the vibrator secured to the universal bar the ribbon is vibrated or moved to expose the writing after each impression.

When it is desired to vibrate the ribbon to expose the writing only after a word has been written, or when the space-key or independent key I is operated, the guide and vibrator M is detached from the universal bar G, and it, or preferably a similar guide and vibrator M', Figs. 3, 6, and 7, adapted for a wider and heavier ribbon L', is attached to the space-bar K. The latter is provided with a holder m⁴, similar to that on the universal bar, in which the bowed spring-shank of the guide and vibrator is adjustably held by friction.

The vibrator M' can be adjusted up or down in its holder by the application of a little force, and by so adjusting the vibrator several different lines along the upper side of the ribbon may be moved into position to receive the impact of the type at the outer ends of the type-bars and still leave the central and lower portion of the ribbon in position to receive the impact of the inner type on the bars when the platen is shifted downwardly for printing with the inner type. By interchanging the ribbon-spools in the usual manner the less-worn portion of the ribbon can be placed uppermost to completely exhaust the ribbon. As the space-bar K is normally held rearward, the vibrator thereon retains the ribbon over the printing-point at all times except when the space or independent key I is depressed, at which time the ribbon is moved forwardly and downwardly to expose the printing. The space-bar is mounted to move forwardly a greater distance than the universal bar and also downwardly, so that the printing is fully exposed, even when the wide ribbon is adjusted to its highest position. The universal bar is arranged to reciprocate nearly in a straight line, as it is not necessary to lower the narrow ribbon much to expose the printing-point. However, the pivotal supports for the universal bar could also be arranged to cause the universal bar to lower, as well as move forwardly. A narrow light ribbon could be used with a guide and vibrator on the space-bar; but as the type-bar action is relieved of the work of vibrating the ribbon the added weight of a wide ribbon is not of so much consequence, while the wide ribbon lessens the cost and work of changing ribbons. With the vibrator on the space-bar the printing-point is exposed at the end of each word and whenever the carriage is moved a letter-space after the use of a punctuation-mark, and it can be exposed at any other time by partly depressing the space-key without causing the carriage to move. Many operators prefer to thus vibrate the ribbon rather than have the ribbon constantly vibrating before them and increasing the work on the type-bar action.

The described construction of the ribbon guides and vibrators and their holders is simple and effective; but guides and vibrators of other construction and other means for detachably connecting them to their supporting and operating bars could be employed.

N, Figs. 1 and 2, represents a curved printing-point index, which is located beneath the platen and pivoted at its rear end in any suitable manner to the carriage-shift frame D, and is swung upwardly against the platen just under the printing-point, as indicated by dotted lines in Fig. 2, by a spring e, Fig. 1. The front end of the index has a

central line or mark to indicate the printing-point. o' is an integral arm on the index, which projects downwardly and bears against a rearward projection on a post P , secured in the vibrator-holder m^4 on the space-bar, and is thereby held down away from the platen, as shown by full lines in Fig. 2, when the narrow-ribbon vibrator M is in use, except when the space-bar K is moved forwardly by the depression of the space-key. The wide-ribbon vibrator M' is provided with a similar projection P' (see Fig. 6) for actuating the index when said vibrator and the wide ribbon are used. When either the post P or wide-ribbon vibrator M' are used, the index is held out of action, except when the space-key I is depressed and the type-bar action is relieved of the work of operating the index. If it is desired to raise the index to operative position after each impression, this can be done by providing a ribbon-vibrator M^2 , Fig. 5, for the universal bar, with an operating projection P^2 for the index. With this vibrator in use the index is moved downwardly away from the platen each time the universal bar is moved rearwardly with the ribbon and allowed to be swung up by its spring when the universal bar moves forwardly with the ribbon and exposes the printing. The ribbon is fed lengthwise or wound slowly from one spool onto the other by mechanism preferably constructed as follows, (see Figs. 2 and 8 12 :) Q represents upright spool-shafts, which are located at opposite sides of the machine and journaled in suitable bearings q in the upper portion of the frame, and q' in a cross-bar q^2 at the lower part of the frame. The spools are placed on the upper ends of these shafts, to which they are splined or otherwise detachably secured so as to turn with the shafts. When the narrow ribbon is used, the spools are held at the proper elevation by suitable washers q^3 , which are omitted when using the wider ribbon and spools. q^4 represents slotted guides, which are removably secured, to the frame adjacent to the spools to lead the ribbon onto the latter. Secured to the lower ends of the spool-shafts are bevel gear-wheels r , adapted to mesh with and be driven by bevel gear-wheels r' , secured to a horizontal drive-shaft R , journaled at its ends in suitable bearings r^2 in the frame-bar q^2 . The central portion of the shaft passes through and bears in holes in two lugs r^3 r^4 , rising from the frame-bar q^2 . The drive-shaft is capable of sliding endwise in its bearings, and when moved one way the gear-wheel at one end will mesh with the gear-wheel on the adjacent spool-shaft and drive the latter, while the opposite movement of the drive-shaft will cause the meshing of the other gear-wheels and the driving of the other

spool-shaft. This arrangement of the spools and operating-shafts is common, and any other means for positively driving either spool as described may be employed.

S represents a spring-barrel, which is loosely mounted to turn on the drive-shaft between the bearing-lugs r^3 r^4 and adjacent to one of them, r^4 , which is preferably provided with a disk portion which closes one side of the barrel. The latter contains a spiral spring s , connected at its inner end to the hub of the barrel and at its outer end to the adjacent bearing-lug r^4 . The barrel has a peripheral flange s' provided for the greater part of its circumference with ratchet-teeth, but having a smooth or untoothed portion s^2 , see Fig. 11. s^3 is a small ratchet-wheel screwed on or otherwise fixed to or formed on the spring-barrel, and T is a toothed escapement-wheel between the spring-barrel and other bearing-lug r^3 and splined or otherwise secured to the drive-shaft to turn therewith while permitting the described endwise movement of the shaft. The escapement-wheel carries a pivoted spring-pressed dog t , which engages the teeth of the small ratchet-wheel of the spring-barrel. The teeth of the small ratchet-wheel extend in the same direction as the teeth of the flange s' of the spring-barrel, so that the latter can be turned independently of the escapement-wheel in a direction to wind the spring—that is, forwardly in the construction shown—but will drive the escapement-wheel and shaft R when turned in the opposite direction by its spring s . Other clutch devices permitting this action would answer.

U represents a pawl pivoted to the space-bar K , with its lower end depending forwardly toward the toothed flange s' of the spring-barrel, but normally held out of engagement therewith; as by a pin u , projecting from the bearing-lug r^4 . The rear portion of the pawl is preferably forked to straddle the universal bar.

V is an escapement-lever pivoted on a projection of the bearing-lug r^3 and having two pallets to engage the teeth of the escapement-wheel T and an arm which extends up between the two parts of the universal bar and between an operating-pin v and another pin, which is preferably one of the transverse pins g^5 of the bar, which are engaged by the arms of the actuating rock-shafts.

The action of this ribbon-drive mechanism is as follows: With each depression of the space-key and forward movement of the space-bar K the pawl U engages the teeth of the flange s' on the spring-barrel and turns the latter forwardly a distance equal, for instance, to four of its teeth and winds the spring to that extent. The dog t holds the spring-barrel against backward movement except as permitted by the escapement, and at this time the escapement-lever V acts

on the escapement-wheel with enough force to prevent the escapement-wheel from turning forward with the driving-spring barrel. With each rearward movement 5 of the universal bar G the pin ν pushes the escapement-lever V rearwardly and releases the lower pallet and engages the upper pallet, as shown in Fig. 10, permitting the escapement-wheel to move slightly, and 10 with the return movement of the universal bar G the pin ν forces the escapement-lever back to normal position and permits a further movement of the escapement-wheel, the complete movement of the universal bar 15 allowing the escapement to move the extent of one tooth. This movement carries the drive-shaft R and spool in gear therewith a corresponding distance and feeds the ribbon a step lengthwise. The ratchet-teeth on the 20 escapement-wheel are shorter than those on the spring-barrel, so that each time the pawl U turns the barrel a distance equal to four teeth on the barrel the spring is wound and power is stored enough to drive the escapement-wheel a distance equal to six of its 25 teeth and move the ribbon for six impressions, or enough for a word of slightly more than the average number of letters. As the spring is wound to the same extent when 30 using the space-lever after a punctuation-point as for a word, the result is that the spring-barrel is soon turned until the smooth part of the flange on the spring-barrel is brought under the end of the pawl U and 35 the spring completely wound up, after which the pawl can only act to wind the spring as much at each depression of the space-key as the escapement-ratchet has permitted the spring-barrel to turn backwardly. The 40 spring-barrel turns backwardly with the escapement-wheel and forwardly independently of it, the barrel having an intermittent oscillating motion and the escapement-wheel an intermittent rotary movement. If the 45 barrel has moved back but a single tooth after the spring has been fully wound, the pawl U takes it forward that much, and if more than one tooth up to four have turned back within reach of the pawl it takes 50 them forward with the next depression of the space-key, thus keeping power enough stored to feed the ribbon for about thirty impressions, and except in the case of several words of unusual length being printed 55 successively the ribbon moves with each character printed. The power stored is sufficient for any probable case of that kind, but the proportions of the parts may be changed to provide for a longer continuous 60 run, if desired. In use this power device relieves the type-keys from all but the slightest part of the work of feeding the ribbon and tends to render the machine easier to operate, capable of greater speed, and of greater 65 power for manifolding.

The ribbon does not feed with each movement of the space-key, but does so with each impression of a type-bar.

Power mechanism analogous to that described for feeding the ribbon, and in which power is stored by the actuation of the space-key or a special key and is liberated or controlled by the actuation of the type-bar keys, can with slight changes or rearrangement of the parts be adapted to machines in which the ribbon arrangement is different from that described and whether the ribbon is vibrated or not.

I claim as my invention—

1. The combination in a type-writing machine, having a keyboard at the front and a carriage-escapement at the rear of the machine, of a universal bar extending rearwardly from the keyboard to the carriage-escapement, and a ribbon guide or vibrator supported by and moving with said universal connection, substantially as set forth.

2. The combination in a type-writing machine having a keyboard at the front and a carriage-escapement at the rear of the machine, of a universal bar extending rearwardly from the keyboard to the escapement, and a ribbon guide or vibrator rigidly connected to the universal bar, substantially as set forth.

3. The combination in a type-writing machine having a keyboard at the front and a carriage-escapement at the rear of the machine, of a universal connection extending rearwardly from the keyboard to the escapement, and a ribbon guide or vibrator detachably connected to and supported by the universal connection, substantially as set forth.

4. The combination in a type-writing machine, having a carriage-escapement, and a series of finger-keys in front thereof, of a universal connection extending rearwardly from the finger-keys to the escapement, and a ribbon guide or vibrator connected to the universal bar and acting to move the ribbon in a line substantially parallel with the connection, substantially as set forth.

5. The combination in a type-writing machine, having a platen, carriage-escapement, and a series of finger-keys arranged in front thereof, of a centrally-arranged universal bar extending rearwardly from the keys beneath the platen and movable in the direction of its length, and a ribbon guide or vibrator operatively connected to the universal bar, substantially as set forth.

6. The combination in a type-writing machine, having a carriage-escapement, and a series of finger-keys, or a universal-bar connection extending from the finger-keys to the escapement and movable in the direction of its length, and a ribbon guide or vibrator secured directly to the universal-bar connection and moving therewith, substantially as set forth.

7. The combination in a type-writing machine, having a carriage-escapement, and a space-key, or a connection between the carriage-escapement and the space-key, and a ribbon guide or vibrator mounted on said connection, substantially as set forth.

8. The combination in a type-writing machine, having a carriage-escapement, and a space-key, or a connection acting to transmit power from the space-key to the escapement, and a ribbon guide or vibrator rigidly secured to the space-key connection, substantially as set forth.

9. The combination in a type-writing machine, having a carriage-escapement, and a space-key, or a connecting-rod between the escapement and space-key, and a ribbon guide or vibrator detachably connected to and supported by the said rod, substantially as set forth.

10. The combination in a type-writing machine, having a platen, a carriage-escapement, and a space-key arranged in front thereof, of a connection extending from the space-key rearwardly beneath the platen to the carriage-escapement and movable in the direction of its length, and a ribbon guide or vibrator operatively connected to said connection, substantially as set forth.

11. The combination in a type-writing machine, having a carriage-escapement, and a space-key arranged in front thereof, of a connection extending rearwardly from the space-key to the escapement and movable in the direction of its length, and a ribbon guide or vibrator secured directly to the space-key connection and moving therewith, substantially as set forth.

12. The combination in a type-writing machine, having a carriage-escapement, and a series of finger-keys, of a universal connection, a key-operated connection for feeding the carriage independently of the universal connection, and means for vibrating the ribbon adapted to be supported by either the universal connection or the key-operated connection, substantially as set forth.

13. The combination in a type-writing machine, having a carriage-escapement, and finger-keys, of a universal bar, a key-actuated connection for operating the escapement independently of the universal bar, and means for vibrating the ribbon adapted to be supported either by the universal bar or by said key-operated connection, substantially as set forth.

14. The combination in a type-writing machine, having a carriage-escapement, and a series of finger-keys, of a universal bar, a space bar or lever, a ribbon-vibrator, and means for mounting the vibrator on either the universal bar or the space-bar, substantially as set forth.

15. The combination in a type-writing machine, having a carriage-escapement, and

finger-keys, of a universal bar, a space-key and connection acting to release the escapement, the universal bar and space-bar moving in opposite directions from their normal position to actuate the escapement, and a ribbon guide or vibrator adapted to be connected to either the universal bar or to the space-bar, substantially as set forth.

16. The combination in a type-writing machine, having a carriage-escapement, and finger-keys, of a universal bar, a ribbon-vibrator adapted to be supported by the universal bar to vibrate the ribbon upon the actuation of the several finger-keys, a key and connection for actuating the carriage-escapement independently of the universal bar, and a ribbon-vibrator adapted to be supported by said connection to vibrate the ribbon only when said key and connection are actuated, substantially as set forth.

17. The combination in a type-writing machine, having a carriage-escapement, and finger-keys, of a universal bar, a space-key and connection for actuating the escapement independently of the universal bar, said universal bar and space-key connection being constructed to independently support a ribbon-vibrator adjacent to the printing-point, substantially as set forth.

18. The combination in a type-writing machine, of a support for a ribbon-vibrator which is actuated each time an impression is made, an independent support for a ribbon-vibrator which is manually operated at will, and a ribbon-vibrator constructed for attachment to and adapted to be supported by one of said supports, substantially as set forth.

19. The combination in a type-writing machine, having a series of type-actuating keys, of a part which is moved by the actuation of the several keys, a part which is actuated independently of said other part by a special key, both of said parts being constructed to support a ribbon-vibrator, and a ribbon-vibrator constructed for attachment to one of said parts, substantially as set forth.

20. The combination in a type-writing machine, of a support for a ribbon-vibrator which is actuated each time an impression is made, an independent support for a ribbon-vibrator which is manually operated at will, a vibrator for a narrow ribbon constructed for attachment to said first support, and a vibrator for a wider ribbon constructed for attachment to said other support, substantially as set forth.

21. The combination in a type-writing machine, of a universal-bar connection, and a space-key connection both having a reciprocating movement but in opposite directions from their normal positions, and a ribbon guide or vibrator attachable to either connection, whereby the machine may be

made to expose the printing-point either after each impression or upon the actuation of the space-key, substantially as set forth.

22. The combination in a type-writing machine having a movable carriage, drive means therefor, and a ribbon, of power-driven mechanism independent of the carriage drive means for feeding the ribbon, means independent of the carriage for operating said ribbon-feed mechanism to store power therein, and means for controlling the ribbon-feed mechanism and allowing it to feed the ribbon, substantially as set forth.

23. The combination in a type-writing machine, having a series of type-bars, a movable carriage, and a ribbon, of power-driven mechanism for feeding the ribbon, a key for operating said ribbon-feeding mechanism to store power therein, and a universal connection with the type-bars whereby the ribbon is caused to feed with each impression of one of the type-bars, substantially as set forth.

24. The combination in a type-writing machine, having a ribbon-feed shaft, and a series of type-bars, and a universal connection with the type-bars, of a driving-spring connected to the ribbon-feed shaft, and means controlled by said universal connection for releasing the spring to turn the shaft after each vibration of one of the type-bars independently of the movement of other parts of the machine, substantially as set forth.

25. The combination in a type-writing machine, of a carriage-escapement, a ribbon-feed shaft, a power-driving mechanism for the same, a series of type-bars, a universal connection, and a ribbon-feed escapement independent of the carriage-escapement actuated by the universal connection to feed the ribbon with each vibration of one of the type-bars, substantially as set forth.

26. The combination in a type-writing machine having a ribbon and a space-key, of power-driving mechanism for the ribbon, and means by which the space-key operates to store power in said driving mechanism for the ribbon, substantially as set forth.

27. The combination in a type-writing machine having a ribbon, a space-key, and a universal bar, of motor-driven mechanism for moving the ribbon, and means operated by the space-key for storing power in said motor and by the universal bar for releasing the motor, substantially as set forth.

28. The combination in a type-writing

machine having a driven carriage, of a ribbon-driving mechanism independent of the carriage drive means, comprising an oscillating coiled spring, an escapement therefor, and means for oscillating the spring and releasing the escapement to move the ribbon, substantially as set forth.

29. The combination in a type-writing machine, having a ribbon-feed device and a series of type-operating keys, of a power-driven wheel, an escapement-wheel connected to said ribbon-feed device, a ratchet and pawl connecting said power-driven wheel and escapement-wheel, and means for turning said power-driven wheel to store power therein and for permitting the escapement-wheel to rotate upon the operation of the type-actuating keys, substantially as set forth.

30. The combination in a type-writing machine, having a carriage, and a ribbon, of a power-driven mechanism acting to feed the ribbon with each impression by one of the type, and means independent of the carriage for operating said power-driven mechanism to store power therein except at such times as it is fully stored, substantially as set forth.

31. The combination in a type-writing machine, having a ribbon, of a power-driven mechanism for moving the ribbon with each impression of a type-bar, a movable part acting to store power in the ribbon-driving mechanism, and means to cause the movable part to pass the power driving mechanism without action at such times as it is fully stored, substantially as set forth.

32. The combination in a type-writing machine, of a printing-point index, a space-bar, and a universal bar, and means to operatively connect either the space-bar or the universal bar to the index, substantially as set forth.

33. The combination in a type-writing machine, of a printing-point index, a space-key connection, a universal-bar connection, and a part adapted for connection with either the space connection or universal connection to operate the index, substantially as set forth.

Witness my hand this 26th day of January, 1905.

EMMIT G. LATTA.
